Attorney

UNITED STATES PATENT OFFICE.

JAMES C. KARNES, OF BUFFALO, NEW YORK.

CARTRIDGE.

Application filed January 6, 1926. Serial No. 79,638.

(GRANTED UNDER THE ACT OF MARCH 3, 1883; 22 STAT. L. 625.)

The invention described herein may be used by the Government, or any of its officers or employees in prosecution of work for the Government, or by any other person in the United States, without payment to me of any royalty thereon, in accordance with the act of March 3, 1883.

This invention relates to a cartridge similar to such as disclosed in my Patent No. 1,681,211, but having the addition of an obturating ring at its base.

In firing at rapidly moving aerial targets, it is necessary, in order to insure a reasonable degree of accuracy, that the "dead time of maneuver" be reduced to a minimum.

Accordingly, I have shown in a prior patent, No. 1,555,061 of Sept. 29, 1925, apparatus for setting a fuse after the round is placed within the gun.

In designing a cartridge for use with such apparatus due regard must be given to the operation of the breech block, the rapid loading of the round, the ejection of the empty case, the effect on the case of the propellant charge and also the transportation of the round. The apparatus should also be independent of the breech block to permit the actuating mechanism to be coupled to a fire control system by which the equivalent of fuse range is automatically and continuously introduced into the device.

To these and other ends, my invention consists in the construction, arrangement and combination of elements, described herein after and pointed out in the claims forming a part of this specification.

A practical embodiment of my invention is illustrated in the accompanying drawing which is a longitudinal sectional view through the breech end of a gun with my improved cartridge loaded in the chamber.

Referring to the drawing by numerals of reference:

The cartridge is substantially of the standard type and comprises a projectile 5 disposed in the usual manner in the forward end of a cartridge case 6. The projectile is equipped with a base time fuse 7 of any suitable type which includes a rotatable positioning element. The base of the cartridge case is formed with a socket 8 for receiving

the hub of a bevel gear wheel 9 adapted to be rotated by the pinion 10 of an actuating mechanism 11, either manually or automatically driven and which it is understood displaces 55 the pinion 10, angular amounts corresponding to values of fuse range. A rod 12 extending axially of the case is fixed to the gear wheel 9 and has its forward end loosely keyed in the positioning element of the fuse 60 so that the rotation of the gear wheel may be imparted through the rod to set the fuse.

For the purpose of igniting the propellant charge 13 in the cartridge case a percussion primer 14 is carried by the gear wheel, 65 the flame from the primer being conducted through a passage 15 and vent holes 16 in the rear end of the rod.

In order to facilitate rotation of the gear wheel 9 the area of contact of the wheel and breech block may be reduced to a minimum. One very effective form of accomplishing this is to provide a ring 17 in the rear face of the wheel, which ring also serves to 70 obturate the gases on discharge. 75

While the application of the invention is shown in connection with a base time fuse it is pointed out that a nose fuse may equally well be employed, the rod 12 extending through the projectile or imparting its 80 movement to a second rod secured to the positioning element of the fuse and forming a part of the projectile.

I claim:

1. A cartridge embodying a fused projectile, a cartridge case having an external socket in its base, a bevel gear wheel formed with a hub disposed in the socket, a primer carried by the gear wheel, a rod fixed to the wheel and extending axially of the case for connection with the fuse of the projectile, and said rod provided with passages to permit the flame from the primer to ignite the propellant charge in the case. 85

2. A cartridge embodying a fused projectile, a cartridge case, a gear wheel rotatably mounted in the base of the case, a primer carried by the gear wheel and a rod fixed to the wheel and detachably connected with the fuse of the projectile. 90

100

JAMES C. KARNES.
